[57] CLAIM

The ornamental design for a design of a cab module for an agricultural implement control system, as shown.

DESCRIPTION

FIG. 1 is a perspective view of a cab module for an agricultural implement control system showing our new design;

FIG. 2 is a front elevation view of our design;

FIG. 3 is a right side elevation view of our design;

FIG. 4 is a rear elevation view of our design;

FIG. 5 is a left side elevation view of our design;

FIG. 6 is a top plan view of our design;

FIG. 7 is a bottom plan view of our design; and,

FIG. 8 is a rear and lower right perspective view thereof.

FIG. 1

FIG. 2

FIG. 3

FIG. 4

FIG. 5

FIG. 6

FIG. 7

FIG. 8
